UNITED STATES PATENT OFFICE.

JOHN H. OVERTON, OF TRENTON, NEW JERSEY, ASSIGNOR TO ESSEX RUBBER COMPANY, OF TRENTON, NEW JERSEY, A CORPORATION OF NEW JERSEY.

MACHINE FOR CUTTING BLANKS.

Application filed April 12, 1919. Serial No. 289,719.

To all whom it may concern:

Be it known that I, JOHN H. OVERTON, a citizen of the United States, and a resident of Trenton, New Jersey, have invented an Improvement in Machines for Cutting Blanks, of which the following is a specification.

My invention relates to machines for cutting blanks out of material which is preferably in sheet form. More particularly, in one of its embodiments, my invention relates to devices for cutting blanks of such material, and especially to devices for cutting blanks from material in a condition approaching a plastic state.

The object of the present invention is to generally improve devices of the character described, so as to render the same simple in construction, and certain and efficient in operation.

By way of example, I have illustrated a preferred embodiment of my invention in the accompanying drawings wherein:

Fig. 1 is a view in end elevation of said embodiment;

Fig. 2 is a front elevation of the same;

Fig. 3 is an end elevation, on an enlarged scale, of a part of the machine comprising said embodiment, certain parts being broken away to make the showing clearer;

Fig. 4 is a front elevational view, on an enlarged scale, of a part of the machine during one stage of its operation;

Fig. 5 is a similar view of said portion during another stage of its operation;

Fig. 6 is a similar view of the same, partly in section, at still another stage of the operation of the machine;

Fig. 7 is a detail view, partly in section and partly in elevation, of a portion of the machine;

Fig. 8 is a plan view of the feeding mechanism showing the same in two stages of its operation;

Fig. 9 is a plan view of one form of a device that may be employed to move the sheet of material towards the feeding mechanism.

Referring to the illustrative embodiment herein shown and described by way of example merely, 1 indicates a source of supply of material from which blanks are to be cut. In the illustrative embodiment herein described, said source of supply

55 may comprise a roll of material in the form of a sheet 2 of rubber stock or other material approaching a plastic state or condition. The roll is rotatably mounted on a shaft 3 supported in suitable bearings 4 mounted on any suitable part, as part 5, of 60 the machine frame.

Since the act of feeding the sheet of material to the cutting mechanism puts considerable strain on the sheet, with consequent possibility of undesirable stretching 65 or distortion of the same, I prefer to provide mechanism for so supplying the cutting mechanism with the material in sheet form from which the blanks are to be made that said sheet of material is presented in 70 a slack condition to the feeding means and the associated blank cutting means. While various devices may be employed for this purpose, I prefer to employ the means illustrated comprising a plurality of feeding 75 cylinders 6 and 7 rotatably mounted in standards 8 which are positioned on arm 9 forming a part of the machine frame.

Preferably cylinder 7 has the surface thereof roughened, while the surface of cylinder 6 is smooth. This arrangement, while providing efficient means for feeding the sheet of material forward, due to the roughness of the surface of cylinder 7, still serves to provide one face of the material 2 with 85 a smooth finish due to the engagement of smooth cylinder 6 with one side of said sheet. While the ends of cylinder 7 are rotatably mounted in fixed bearings 12, cylinder 6 is preferably mounted in bearings 10 90 slidably positioned in standards 8. Compression springs 11 are inserted between the fixed bearings 12 of cylinder 7 and the slideable bearings 10 of cylinder 6. Adjustable means, such as the screws 13 mounted in standards 8, may be provided to move bearings 10 towards or away from bearings 12 to thereby vary the pressure exerted on springs 11 to vary the pressure exerted in turn by cylinders 6 and 7 on sheet 2.

100 Any suitable means may be employed for actuating cylinders 6 and 7 to thereby advance sheet 2. In order to suitably support said sheet during its actuation I provide a platform 14 mounted, as shown, on arms 9 of the machine frame. Such actuating means may, as illustrated, comprise a friction disk 15 mounted on main drive shaft 105

16 which is suitably driven, as by means of the friction pulleys 17, from any suitable source of power. Friction disk 15 makes frictional driving contact with a friction pinion 18 suitably mounted on a shaft 19 which is supported in suitable bearings 20 carried by any suitable part of the machine frame, as by one of the standards 21. Shaft 19 carries at its upper end a 10 bevel or other gear 22 which meshes with a similar gear 23 carried by a shaft 24 which carries the rotatably mounted lower roughened cylinder 7.

Suitable means are provided for feeding 15 the sheet of material to the cutting mechanism. Preferably the action of feeding the sheet 2 to the cutting mechanism is intermittent, and the feeding means are preferably so disposed as to contact with a portion 20 of the sheet of material of sufficient area to prevent substantial distortion of the material during the feeding operation. Such an arrangement is desirable so that the finished product or blank may be of uniform 25 density and character.

For this purpose I may use the means illustrated more particularly in Figs. 3, 7 and 8 of the drawing. Such means may comprise a cam 25 provided with a cam surface 26, said cam being mounted on the main drive shaft 16. Cam surface 26 engages a roller 27 mounted at the junction of two link members 28 and 29, the link member 29 being pivotally mounted at 30 on a suitable part, as a part 31, of the machine frame. Link member 28 is pivotally connected, as at 32, to a bar 33 which is provided with an adjustable pivot 34.

At its upper end bar 33 carries a spherical 40 or similar ball member 35 which engages a socket 36 in an actuating member 37 pivoted at 38 to any suitable portion of the machine frame, as platform 39. At its other end actuating member 37 is provided with 45 a plurality of forked portions 40 and 41 through which passes a roller bearing 42. Roller bearing 42 rides within a slot or groove 43 defined between a plurality of members 44 and 45, suitably mounted, as 50 on platform 39. In order to raise or elevate members 44 and 45 so that lower forked member 41 may pass under the same, I provide blocks 46 for suitably positioning members 44 and 45 at a predetermined distance 55 from platform 39.

Adjustable pivot 34 may be adjusted by means of a slidible bearing 34^a which has a threaded aperture cooperating with a screw 34^b which is mounted in any suitable 60 portion of the machine frame, as at 34^c, so as to be rotatable to raise or lower bearing 34^a and its associated pivot 34 to thereby vary the throw or travel of the feeding mechanism in each direction.

65 Pivotsly associated with roller bearing

42 is a connecting member 47 to which is adjustably attached, as at 48, a second connecting member 49 which is in turn attached to the feeding mechanism, generally designated by reference numeral 50.

70 While various types of feeding mechanisms may be employed, I prefer to use the means illustrated, comprising a plurality of tracks or bars 51 attached, as at 52, to a member 53 suitably connected to member 49. These tracks or bars 51 engage grooves 54 in the standard 55 which may be suitably positioned, as on a platform 56, forming a part of the machine frame. Member 53, as more clearly shown 80 in Fig. 8, carries a plurality of blocks 57. Blocks 57 are provided with a plurality of bearings 58 for pivotally supporting a catch member 59 having a serrated edge 60. Catch member 59 is suitably attached to a 85 rod or other support 61. Spring or other means, such as the two coil springs 62, are provided for urging member 59 so as to bring its serrated edge downwardly against the sheet of material 2.

90 A guide member or lip 63 is provided for guiding the sheet of material 2 towards the feeding and cutting mechanism. Guiding member or lip 63 may be suitably supported, as by mounting the same between blocks 95 57. In order to more accurately guide the sheet 2 to the feeding and cutting mechanism, I may provide also a plurality of side members or lips 64. Side members 64 are slidably mounted on a rod 65 which is carried by the blocks or projections 66 which are in turn carried by blocks 57. Any suitable means, such as the screws shown, may be employed for positioning lips 64 in their adjusted positions.

105 The feeding mechanism proper comprises an upper feeding member 67 and a lower feeding member 68. The upper feeding member 67 comprises a plate 69 which is attached to a plurality of flexible strips or 110 members 70. Suitably attached to the inner end of plate 69 are a plurality of spaced spring fingers 71. The lower feeding member 68 comprises a plate 72 of springy material provided with a plurality of spaced 115 spring fingers 73, preferably integral with plate 72. Plates 69 and 72 are maintained in proper spaced relation to each other by means of end blocks 74. The flexible members 70 are mounted on suitable bolts 75 and 120 are pulled down by means of a plurality of springs 76 mounted upon a plurality of studs 77, preferably carried by plate 53. The action of springs 76 tends to raise feeding members 67 and 68 upwardly and slightly 125 away from member 53.

130 The feeding mechanism just described operates to intermittently feed the sheet of material 2 to the cutting mechanism, generally designated by reference numeral 78. In this

connection it may be stated that the serrated edge of member 59 and the disposition of such member serve to help the forward feeding motion of the sheet 2 to the cutting mechanism by preventing said sheet from slipping backwards, while in the return or backward movement of the feeding mechanism the disposition of member 59 is such as to permit the ready withdrawal of the feeding mechanism from the sheet which is held in its advanced position by means subsequently to be set forth.

The cutting mechanism 78 may comprise any suitable means, but preferably the means illustrated, consisting of a hollow die 79 removably attached, as at 80, to platform 56, which platform is provided with an opening 81 therethrough and communicating and in alignment with the opening 82 of said hollow die 79.

Cooperating with said hollow die 79 is a cutting block 83 carried by a suitable number of, herein shown as four, studs or posts 84 which are suitably attached to the head 25 or cross member 85 which is in turn attached to the rods or pitmans 86. These rods or pitmans are preferably, as shown, four in number, and are reciprocably supported in any suitable portion of the machine frame, 30 herein shown as comprising the bearings 87. At each end of the machine a pair of the rods or pitmans 86 is attached to a cross member 87 to which is pivotally connected, as at 88, an operating member 89 attached 35 to eccentric sleeve 90. Said eccentric sleeve 90 is mounted on an eccentric 91 which is in turn keyed or otherwise attached to shaft 16.

It will thus be noted that the rotation of shaft 16 carrying eccentric 91 about which 40 is positioned the eccentric sleeve 90 serves to reciprocate its associated pair of rods or pitmans 86, to thereby reciprocate head 85 and cutting block 83 carried thereby towards and away from the cutting edge 92 of a hollow die 79. In this connection it may be stated that as a result of the provision of spring members 76, which act to raise feeding members 67 and 68 away from member 53, the sheet of material 2 carried between said 45 feeding members 67 and 68 and intermittently actuated in a forward direction over the cutting die 79, will be slightly raised away from cutting edge 92, except when cutting block 83 depresses the sheet into operating 50 contact with said edge 92. On raising the cutting block, after the cutting operation is completed, spring 76 will then operate to move the waste stock away from the edge of the cutting die to enable the sheet of material 2 to be advanced without hindrance 55 for the next cutting operation.

I provide suitable means for retaining the sheet of material 2 in position for the cutting operation, during the withdrawal of the 60 feeding members 67 and 68. Such means

may comprise the means illustrated, consisting of a vertically movable retaining member 93 reciprocably mounted in a plurality of opposed slots 94 in standards 55 for fixedly retaining the sheet 2 in a forward position during the withdrawal of feeding members 67 and 68.

Retaining member 93 is preferably provided with a plurality of projections 95 and 96 to which are suitably attached contraction springs 97 and 98, one end of each spring being attached to its respective member 95 or 96, as the case may be, while the other ends are attached to the respective standards 55. These springs urge members 93 downwardly. Member 93 is provided at its lower edge with a plurality of teeth or pins 99 which, when member 93 is in its lowermost or operative position, engage sheet 2 intermediate the over-lapping pairs 85 of spring fingers 71 and 73 of feeding members 67 and 68, respectively.

As shown more clearly in Fig. 7, each standard 55 is provided with a dog 100 pivoted, as at 101, to said standard. The upper or detent end 102 of each dog 100 is provided with an expansion spring 103, one end of which is attached, as at 104, to said detent end 102 of dog 100, while the other end of the spring is attached as at 105 to a 95 suitable portion of standard 55. The other or actuating end of each dog 100, here designated by the reference numeral 106, is adapted to intermittently engage a wedge shaped cam member 107 which is carried by 100 its respective reciprocating track member 53.

Also attached to each standard 55, as by being pivoted thereto, as at 108, is a second dog 109 having an operative or raising end portion 110, and an actuated portion 111 105 which is adapted to be intermittently engaged by the respective blocks 112 carried by cutting block 83. The retaining member 93 is provided with a plurality of oppositely disposed projections 113 for engagement with the retaining ends 102 of dog 100. The actuating end 111 of each dog 109 is provided with a stop or extension 114 to limit the angle of oscillation of said dog during the operation of the machine. Preferably member 93 is provided at each end thereof with a cut away portion 93' for engagement with the detent end 102 of the respective dogs 100.

Suitable means are provided for ejecting 120 the cut blank through the hollow die 78 when the cutting operation is completed. For this purpose I prefer to use the mechanism illustrated comprising, as best shown in Figs. 4, 5, and 6, an ejecting member 115 mounted on a plurality of members or studs 116 which pass through cutting block 83 and also through a pad or buffer 117, which may be of rubber or the like, and which is adapted to take up the shock of operation of 125 130

ejecting member 115. Studs 116 are carried by a plate-like member 118 which is pivotally carried by a member 119 pivoted to member 118, as at 120. Member 119 is pivoted to an operating lever 121, as at 121', which is in turn pivoted, as at 122, to any suitable portion of the machine frame, as head 85.

Lever 121 carries at its inner end a projection 123 for engagement with a pawl 124 which is pivoted, as at 125, to any suitable portion of the machine frame, as to a block 126 attached to head 85. At one end, pawl 124 is provided with an expansion spring 127 which tends to maintain said end of pawl 124 in depressed or low position. Pawl 124 is provided with a pin 128 which engages in a slot 129 of a second lever 130, also pivoted to any suitable portion of the machine frame, as to pivot 122. Lever 130 is provided with a cut away or slotted portion 131 to permit said lever to move without interruption past pivot 125.

Passing through member 118 are a plurality of studs or posts 132 about each of which is a coiled expansion spring 133 normally tending to force member 118 downwardly against cutting block 83 to thereby move ejecting member 115 into downward or operative position.

Cooperating with the other ends of levers 121 and 130 is a latch member 134 pivoted as at 135 to any suitable portion of the machine frame, as to the block 136. Latch member 134 is forwardly pressed by an expansion spring 137 interposed between the upper free end of latch member 134 and any suitable portion of the machine frame, as standard 138. Latch member 134 is provided with a catch portion 139 and a cam or operating portion 140, the catch portion 139 cooperating with the rear end of lever 130, while the cam portion cooperates with the rear end of lever 121.

The operation of the machine will be substantially clear from the foregoing description. The material of which the blank, such as the sole blank shown herein for purposes of illustration, is to be made, is unwound from roll 1, and the sheet 2 is forwardly fed by means of rollers 6 and 7 to the feeding and cutting mechanism. The speed of operation of feeding rollers 6 and 7 is so chosen and the amount of material between the rollers and the feeding mechanism is so predetermined that sheet 2 will be presented in a slack condition to the feeding mechanism to prevent distortion of the same during the feeding operation.

For the purpose of thus regulating the speed which rollers 6 and 7 feed the sheet of material 2 towards the feeding and severing mechanism, I may utilize the mechanism more clearly shown in Fig. 1, and comprising a collar 141 rotatably carrying friction

pinion 18. Collar 141 may be adjusted by means of a screw member 142 and an adjustable screw head 143, said screw and head being carried by member 141 attached to any suitable portion of the machine frame, as to standard 89. The actuation of screw 142 by means of head 143 mounted on bearings 144, through which shaft 19 freely passes, serves to move friction pinion 18 towards or away from the center of friction disk 15, to thereby vary the speed of rotation of shaft 19 and therefore of feeding rollers 6 and 7.

The sheet of material 2, preferably in the slack condition described, passes under lip 63, between end lips 64, and in between the upper and lower reciprocating feeding members 67 and 68. As already stated, I prefer to make the area of contact of said feeding members with the sheet 2 of such size as to prevent substantial distortion of the material during the feeding operation. For this purpose I may provide the spaced spring fingers 71 and 73 which are normally pressed towards each other and yieldingly hold and retain between them a substantial area of the sheet 2 during the forward feeding operation.

The feeding mechanism is forwardly actuated by means of cam member 25, provided with the cam surface 26, through the mediation of roller 27, actuating member 33, adjustably pivoted at 34, actuating member 35, and the pivoted, forked member 37 which is attached to the feeding mechanism 50 by means of plate 49. As the sheet is forwardly fed, it is prevented from slipping backwards between fingers 71 and 73 by means of catch member 59 having the serrated edge 60 and urged downwardly against sheet 2 by means of the springs 62. It may here be stated, however, that the catch member 59 does not hinder the withdrawal of the feeding mechanism in its reverse or backward movement, in view of the forwardly inclined position of said catch member 59.

The forward actuation of the feeding mechanism brings such mechanism and the sheet of material 2 carried thereby into the position illustrated in full lines in Fig. 8, the cutting die being shown in dotted lines at 79. In this position it will be noted that the sheet of material 2 and the feeding mechanism carrying the same is well beyond and over cutting die 69. At this point of the operation of the feeding mechanism, the vertically movable retaining member 93 will be substantially in the position shown in Fig. 7 of the drawing. The further actuation of the feeding mechanism, in the direction indicated by the horizontal arrow in Fig. 7, operates to bring the wedge-shaped cam member 107 against the actuating end 106 of each dog 100 to thereby pivotally move the detent end 102 of said dog 100 out from under projection 113 against the ac-

tion of spring 103. This causes member 93 to drop downwardly under the action of springs 97 so as to bring pins or teeth 99 into engagement with sheet 2 at those portions thereof which lie between the opposing pairs of fingers 71 and 73.

At this point the feeding mechanism 50 will begin its reverse or backward movement. The sheet 2 will however remain in its forward or advanced position due to its being retained in such position by the action of retaining member 93. It will also be noted, as already stated, that member 59 will not prevent the withdrawal of the feeding mechanism although during the forward feeding movement it compels the sheet 2 to advance with the feeding mechanism.

When the feeding mechanism 50 commences its return movement back to its original position, as indicated by the dotted lines in Fig. 8, the cutting block 83 starts its downward movement. The reciprocation of cutting block 83, as already made clear, is brought about by its attachment by means of posts 84 to head 85 which is attached to the rods or pitmans 86, which are in turn attached to the eccentric sleeves 90 so as to be reciprocated thereby, to thereby reciprocate head 85 and cutting block 83 carried thereby.

As cutting block 83 approaches that portion of sheet 2 which is over the cutting die 79, the feeding mechanism will have returned to its rear or backward position, illustrated in dotted lines in Fig. 9. The further actuation of cutting block 83 in a downward direction first brings the ejecting member 115 into contact with that portion of the sheet 2 which lies immediately within the outlines of cutting edge 92 of die 79. This engagement will serve to position or bring sheet 2 to bear on the cutting die 79 against the action of springs 76 which normally tend to raise sheet 2 away from the cutting edge 92 of die 79.

As cutting block 83 continues to descend, it is brought to bear with considerable pressure against sheet 2 to thereby cause cutting edge 92 of die 79 to sever sheet 2 to form a blank 145, as more clearly shown in Fig. 6. The cutting action resulting in the formation of blank 145 corresponds to the lowermost position of cutting block 83. Thereafter said block, head 85, and associated mechanism start their return or upward movement.

Before said upward movement is commenced, however, the downward movement of block 83 and its associated end blocks 112 brings said end blocks into contact with the actuating ends 111 of dogs 109. This causes said dogs to be moved pivotally in a downward direction at said ends 111, as indicated by the vertical arrow in Fig. 7, thereby causing the elevation of actuating ends 110

of said dogs 109. This last action causes member 93 to be once more elevated into raised position so as to cause projections 113 to be engaged by retaining ends 104 of dogs 100. This action will be permitted since by this time the wedge-shaped cams 107 will have moved to the left, as illustrated in Fig. 7, to once more permit springs 103 to inwardly press ends 102 of dogs 100 to bring said ends into engagement with projections 113. The raising of member 93 is brought about by the engagement of ends 110 of dogs 109 with the cut away portions 93' of said member 93.

Shortly after cutting block 83 has started its return or upward movement, and member 93 has been restored to its raised or elevated position, ejecting member 115 will be actuated to remove blank 145 from hollow die 79. It may here be noted that, as already stated, the action of springs 76 will already have served to raise the waste material at the end of the sheet 2 slightly away from the cutting edge 92 of die 79, such springs serving before the cutting operation to maintain sheet 2 slightly above and free from said cutting edge.

As the reciprocating head 85 and the associated cutting block 83 and other mechanism carried by said head start on their return movement, the rear end of lever 130 will be retained by the catch portion 139 of latch member 134. The continued rise of head 85 and pivot 122 associated with said head causes lever 130, by the engagement of slot 131 with pin 125 on pawl 124, to tilt or pivot pawl 124 about pivot 125. This action moves pawl 124 out of engagement with the projection 123 of lever 121. The release of lever 121, by the withdrawal of pawl 124, permits member 119 carrying member 118, which in turn carries the ejecting member 115, to drop, to thereby eject blank 145 from hollow die 79. This action is rendered more positive by the provision of a plurality of coiled expansion springs 133 mounted about a plurality of pins or posts 132 positioned between head 85 and cutting block 83.

The continued rise of head 85 carrying pivot 122, to which levers 121 and 130 are pivoted, causes lever 121 to be gradually elevated by the engagement of the rear end of said lever with the cam portion 140 of latch member 134, an expansion spring 137 being provided to keep latch member 134 in contact with the rear ends of levers 121 and 130 at the desired periods of the operation of the machine. When such lever 130 has been raised sufficiently to bring projection 123 and the associated members 115 and 118 into a more elevated position, spring 127, operating at the rear end of pawl 124 acts to once more bring said pawl into retaining engagement with projection 123 of lever 121, as shown in Fig. 4. The ejecting member is 130

now ready for the next ejection operation, as already described.

The ejected blank 145 falls onto a conveyor 148, more clearly shown in Figs. 1 and 5 2, said conveyor passing beneath the aligned openings 78 and 81 of the hollow die 79 and the platform 82, respectively. Said conveyor 148 is moved by means of a pulley 149 mounted on the main drive shaft 16 of the 10 machine. The conveyor passes over a suitable guide roll 150 in order to minimize friction and wear during the operation of the same.

It is of course to be understood that my 15 invention is not to be limited to the specific embodiment herein shown and described by way of example merely.

What I claim is:

1. In a machine for cutting blanks of a 20 sheet of material in a condition approaching a plastic state, the combination of reciprocatory feeding means engaging a portion of said material of sufficient area to prevent substantial distortion of the material during 25 the feeding operation, cutting means operating alternately with the feeding means, and constantly acting feeding means arranged to draw the sheet from a source of supply and deliver it in slack condition to the reciprocatory means.

2. In a machine for cutting blanks of a sheet of material in a condition approaching a plastic state, feeding means comprising a plurality of members contacting with both 35 sides of a portion of said material of sufficient area to prevent substantial distortion of the material during the feeding operation, means for imparting reciprocating motion to said feeding means, and means associated 40 with said feeding means for assisting said feeding means in advancing said material during the forward movement of said feeding means while permitting the same to be withdrawn during the backward movement 45 of the same without substantial backward movement of said material.

3. In a machine for cutting blanks of a sheet of material in a condition approaching a plastic state, feeding means comprising a 50 plurality of members resiliently contacting with both sides of a portion of said material of sufficient area to prevent substantial distortion of the material during the feeding operation, means for imparting reciprocating motion to said feeding means, and means associated with said feeding means for assisting said feeding means in advancing said material during the forward movement 55 of said feeding means while permitting the same to be withdrawn during the backward movement of the same without substantial backward movement of said material.

4. In a machine for cutting blanks of a sheet of a material in a condition approach- 60 ing a plastic state, feeding means compris- 65

ing a plurality of members resiliently holding between them a portion of said material, one of said members being provided with a plurality of spaced, resilient, material-engaging portions. 70

5. In a machine for cutting blanks of a sheet of a material in a condition approaching a plastic state, feeding means comprising a plurality of members resiliently holding between them a portion of said material, 75 each of said members being provided with a plurality of spaced, resilient, material-engaging portions.

6. In a machine for cutting blanks of a sheet of a material in a condition approaching a plastic state, feeding means comprising a plurality of members resiliently holding between them a portion of said material of sufficient area to prevent substantial distortion of the material during the feeding operation, one of said members being provided with a plurality of spaced, resilient, material-engaging portions. 80 85

7. In a machine for cutting blanks of a sheet of a material in a condition approaching a plastic state, feeding means comprising a plurality of members resiliently holding between them a portion of said material of sufficient area to prevent substantial distortion of the material during the feeding operation, each of said members being provided with a plurality of spaced, resilient, material-engaging portions. 90 95

8. In a machine for cutting blanks of a sheet of a material in a condition approaching a plastic state, feeding means comprising a plurality of members resiliently holding between them a portion of said material, one of said members being provided with a plurality of spaced, resilient, material-engaging portions, means for imparting reciprocating motion to said feeding means, and means associated with the feeding means for assisting the same in advancing said material during the forward movement of said feeding means while permitting the same to be withdrawn during the backward movement of the same without substantial backward movement of said material. 100 110

9. In a machine for cutting blanks of a sheet of a material in a condition approaching a plastic state, feeding means comprising a plurality of members resiliently holding between them a portion of said material, each of said members being provided with a plurality of spaced, resilient, material-engaging portions, means for imparting reciprocating motion to said feeding means, and means associated with the feeding means for assisting the same in advancing said material during the forward movement of said feeding means while permitting the same to be withdrawn during the backward movement of the same without substantial backward movement of said material. 115 120 125 130

10. In a machine for cutting blanks of a sheet of a material in a condition approaching a plastic state, feeding means comprising a plurality of members resiliently holding between them a portion of said material of sufficient area to prevent substantial distortion of the material during the feeding operation, one of said members being provided with a plurality of spaced, resilient, material-engaging portions, means for imparting reciprocating motion to said feeding means, and means associated with the feeding means for assisting the same in advancing said material during the forward movement of said feeding means while permitting the same to be withdrawn during the backward movement of the same without substantial backward movement of said material.
11. In a machine for cutting blanks of a sheet of a material in a condition approaching a plastic state, feeding means comprising a plurality of members resiliently holding between them a portion of said material of sufficient area to prevent substantial distortion of the material, each of said members being provided with a plurality of spaced, resilient, material-engaging portions, means for imparting reciprocating motion to said feeding means, and means associated with the feeding means for assisting the same in advancing said material during the forward movement of said feeding means while permitting the same to be withdrawn during the backward movement of the same without substantial backward movement of said material.
12. In a machine for cutting blanks of a sheet of a material in a condition approaching a plastic state, feeding means comprising a plurality of members contacting with both sides of a portion of said material of sufficient area to prevent substantial distortion of the material during the feeding operation, means for imparting reciprocating motion to said feeding means, means associated with said feeding means for assisting said feeding means in advancing said material during the forward movement of said feeding means while permitting the same to be withdrawn during the backward movement of the same without substantial backward movement of said material, and means for presenting a portion of said material in slack condition to said feeding means.
13. In a machine for cutting blanks of a sheet of a material in a condition approaching a plastic state, feeding means operable to alternately grip and release the sheet comprising a plurality of members resiliently contacting with both sides of a portion of said material of sufficient area to prevent substantial distortion of the material during the feeding operation, and
- means for presenting a portion of said material in slack condition to said feeding means.
14. In a machine for cutting blanks of a sheet of a material in a condition approaching a plastic state, feeding means comprising a plurality of members resiliently contacting with both sides of a portion of said material of sufficient area to prevent substantial distortion of the material during the feeding operation, means for imparting reciprocating motion to said feeding means, means associated with said feeding means for assisting said feeding means in advancing said material during the forward movement of said feeding means while permitting the same to be withdrawn during the backward movement of the same without substantial backward movement of said material, and means for presenting a portion of said material in slack condition to said feeding means.
15. In a machine for cutting blanks of a sheet of a material in a condition approaching a plastic state, feeding means comprising a plurality of members contacting with both sides of a portion of said material of sufficient area to prevent substantial distortion of the material during the feeding operation, means for imparting reciprocating motion to said feeding means, means associated with said feeding means for assisting said feeding means in advancing said material during the forward movement of said feeding means while permitting the same to be withdrawn during the backward movement of the same without substantial backward movement of said material, and means operating to positively retain said material in its advanced position during the backward movement of the feeding means.
16. In a machine for cutting blanks of a sheet of a material in a condition approaching a plastic state, feeding means comprising a plurality of members resiliently contacting with both sides of a portion of said material of sufficient area to prevent substantial distortion of the material during the feeding operation, means for imparting reciprocating motion to said feeding means, means associated with said feeding means for assisting said feeding means in advancing said material during the forward movement of said feeding means while permitting the same to be withdrawn during the backward movement of the same without substantial backward movement of said material, and means operating to positively retain said material in its advanced position during the backward movement of the feeding means.
17. In a machine for cutting blanks of a sheet of a material in a condition approaching a plastic state, feeding means comprising a plurality of members re-

silently holding between them a portion of said material, one of said members being provided with a plurality of spaced, resilient, material-engaging portions, means 5 for imparting reciprocating motion to said feeding means, means associated with the feeding means for assisting the same in advancing said material during the forward movement of said feeding means while permitting the same to be withdrawn during the backward movement of the same without substantial backward movement of said material, and means operating to positively retain said material in its advanced position 15 during the backward movement of the feeding means.

18. In a machine for cutting blanks of a sheet of a material in a condition approaching a plastic state, feeding means 20 comprising a plurality of members resiliently holding between them a portion of said material, each of said members being provided with a plurality of spaced, resilient, material-engaging portions, means 25 for imparting reciprocating motion to said feeding means, means associated with the feeding means for assisting the same in advancing said material during the forward movement of said feeding means while permitting the same to be withdrawn during the backward movement of the same without substantial backward movement of said material, and means operated by said feeding means to positively retain said material in 30 its advanced position during the backward movement of the feeding means.

19. In a machine for cutting blanks of a sheet of a material in a condition approaching a plastic state, feeding means comprising 40 a plurality of members resiliently holding between them a portion of said material of sufficient area to prevent substantial distortion of the material during the feeding operation, one of said members being provided with a plurality of spaced, resilient, material-engaging portions, means for imparting reciprocating motion to said feeding means, means associated with the feeding means for assisting the same in advancing said material during the forward movement of said feeding means while permitting the same to be withdrawn during the backward movement of the same without substantial backward movement of said material, and means operating to positively retain said material in its advanced position during the backward movement of the feeding means.

20. In a machine for cutting blanks of a sheet of a material in a condition approaching a plastic state, feeding means comprising 60 a plurality of members resiliently holding between them a portion of said material of sufficient area to prevent substantial distortion of the material, each

of said members being provided with a plurality of spaced, resilient, material-engaging portions, means for imparting reciprocating motion to said feeding means, means associated with the feeding means for assisting the same in advancing said material during the forward movement of said feeding means while permitting the same to be withdrawn during the backward movement of the same without substantial backward movement of said material, and means operated by said feeding means to positively retain said material in its advanced position during the backward movement of the feeding means. 80

21. In a machine for cutting blanks of a sheet of a material in a condition approaching a plastic state, feeding means comprising a plurality of members contacting with both sides of a portion of said material of sufficient area to prevent substantial distortion of the material during the feeding operation, means for imparting reciprocating motion to said feeding means, means associated with said feeding means for assisting said feeding means in advancing said material during the forward movement of said feeding means while permitting the same to be withdrawn during the backward movement of the same without substantial backward movement of said material, means for presenting a portion of said material in slack condition to said feeding means, and means operating to positively retain said material in its advanced position during the backward movement of the feeding means. 90

22. In a machine for cutting blanks of a sheet of material in a condition approaching a plastic state, feeding means comprising a plurality of members resiliently contacting with both sides of a portion of said material of sufficient area to prevent substantial distortion of the material during the feeding operation, means for imparting reciprocating motion to said feeding means, means associated with said feeding means for assisting said feeding means in advancing said material during the forward movement of said feeding means while permitting the same to be withdrawn during the backward movement of the same without substantial backward movement of said material, means for presenting a portion of said material in slack condition to said feeding means, and means operated by said feeding means to positively retain said material in its advanced position during the backward movement of the feeding means. 110

23. In a machine for cutting blanks, reciprocating feeding means for intermittently advancing material in the form of a sheet, cutting means intermittently operating transversely of said sheet to cut blanks from the same at those intervals of the intermittent advance of the same when the 120

- sheet is at rest, and means intermittently actuated to grip the sheet to positively retain said sheet in position during the return movement of said feeding means.
- 5 24. In a machine for cutting blanks, reciprocating feeding means for intermittently advancing material in the form of a sheet, cutting means intermittently operating transversely of said sheet to cut blanks from the same at those intervals of the intermittent advance of the same when the sheet is at rest, and means operated by said feeding means for positively retaining said sheet in position during the return movement of said feeding means.
- 10 25. In a machine for cutting blanks, reciprocating feeding means for intermittently advancing material in the form of a sheet, cutting means intermittently operating transversely of said sheet to cut blanks from the same at those intervals of the intermittent advance of the same when the sheet is at rest, and means operated by said feeding means for positively retaining said sheet in position during the return movement of said feeding means and by said cutting means to release said sheet for its next forward movement.
- 15 26. In a machine for cutting blanks, reciprocating feeding means for intermittently advancing material in the form of a sheet, cutting means intermittently operating transversely of said sheet to cut blanks from the same at those intervals of the intermittent advance of the same when the sheet is at rest, and means operating transversely of said sheet and operated by said feeding means for positively retaining said sheet in position during the return movement of said feeding means.
- 20 27. In a machine for cutting blanks, reciprocating feeding means for intermittently advancing material in the form of a sheet, cutting means intermittently operating transversely of said sheet to cut sole blanks from the same at those intervals of the intermittent advance of the same when the sheet is at rest, and means operating transversely of said sheet and operated by said feeding means for positively retaining said sheet in position during the return movement of said feeding means and by said cutting means to release said sheet for its next forward movement.
- 25 28. In a machine for cutting blanks, reciprocating feeding means for intermittently advancing material in the form of a sheet, cutting means intermittently operating transversely of said sheet to cut blanks from the same and comprising a cutting die having an opening permitting the blank to fall therethrough when the cutting operation is completed, a cutting block co-operating with said die, said die and block being relatively movable towards each other to perform the cutting operation and away from each other when the cutting operation is completed, and means for removing the blank from the die when the cutting operation is completed.
- 30 29. In a machine for cutting blanks, reciprocating feeding means for intermittently advancing material in the form of a sheet, cutting means intermittently operating transversely of said sheet to cut blanks from the same and comprising a cutting die having an opening permitting the blank to fall therethrough when the cutting operation is completed, a cutting block co-operating with said die, said die and block being relatively movable towards each other to perform the cutting operation and away from each other when the cutting operation is completed, and means operated by the cutting means for removing the blank from the die when the cutting operation is completed.
- 35 30. In a machine for cutting blanks, reciprocating feeding means for intermittently advancing material in the form of a sheet, cutting means intermittently operating transversely of said sheet to cut blanks from the same and comprising a cutting die having an opening permitting the blank to fall therethrough when the cutting operation is completed, a cutting block co-operating with said die, said die and block being relatively movable towards each other to perform the cutting operation and away from each other when the cutting operation is completed, and means for removing the blank and the sheet from the die when the cutting operation is completed.
- 40 31. In a machine for cutting blanks, reciprocating feeding means for intermittently advancing material in the form of a sheet, cutting means intermittently operating transversely of said sheet to cut blanks from the same and comprising a cutting die having an opening permitting the blank to fall therethrough when the cutting operation is completed, a cutting block co-operating with said die, said die and block being relatively movable towards each other to perform the cutting operation and away from each other when the cutting operation is completed, means for removing the sheet from the die when the cutting operation is completed, and means operated by the cutting means for removing the blank from the die.
- 45 32. In a machine for cutting blanks, reciprocating feeding means for intermittently advancing material in the form of a sheet, cutting means intermittently operating transversely of said sheet to cut blanks from the same and comprising a cutting die having an opening permitting the blank to fall therethrough when the cutting operation is completed, a cutting block co-operating with said die, said die and block being relatively movable towards each other to perform the cutting operation and away from each other when the cutting operation is completed, and means for removing the blank from the die when the cutting operation is completed.

relatively movable towards each other to perform the cutting operation and away from each other when the cutting operation is completed, means associated with the 5 feeding means for removing the sheet from the die when the cutting operation is completed, and means operated by the cutting means for removing the blank from the die.

33. In a machine for cutting blanks of 10 material in sheet form, feeding means for intermittently advancing said material, cutting means intermittently operating transversely of said sheet and comprising a cutting die having an opening therethrough, 15 a support for said die having an opening therethrough corresponding to and in alignment with said first-mentioned opening, a cutting block, said die and block being relatively movable towards each other to perform 20 the cutting operation and away from each other when the cutting operation is completed, means for freeing the blank from the die and ejecting the same through said openings, and means for moving said 25 receiving means.

34. In a machine for cutting blanks of 30 material in sheet form, feeding means for intermittently advancing said material, cutting means intermittently operating transversely of said sheet and comprising a cutting die having an opening therethrough, a support for said die having an opening therethrough corresponding to and in alignment with said first-mentioned opening, a cutting 35 block, means for moving said block toward said die to perform the cutting operation and away from said die when the cutting operation is completed, means for freeing the blank from the die and ejecting the same through 40 said openings, means for receiving the blank when it falls through said openings, and means for moving said receiving means.

35. In a machine for cutting blanks of 45 material in sheet form, feeding means for intermittently advancing said material, cutting means intermittently operating transversely of said sheet and comprising a cutting die having an opening therethrough, a support for said die having an opening therethrough corresponding to and in alignment with said first-mentioned opening, a cutting 50 block, said die and block being relatively movable towards each other to perform the cutting operation and away from each other when the cutting operation is completed, means operated by the cutting means for freeing the blank from the die and ejecting the same through said openings, means for 55 receiving the blank when it falls through 60

said openings, and means for moving said receiving means.

36. In a machine for cutting blanks of 65 material in sheet form, feeding means for intermittently advancing said material, cutting means intermittently operating transversely of said sheet and comprising a cutting die having an opening therethrough, a support for said die having an opening therethrough corresponding to and in alignment 70 with said first-mentioned opening, a cutting block, means for moving said block toward said die to perform the cutting operation and away from said die when the cutting operation is completed, means operated by the cutting means for freeing the blank from the die and ejecting the same through 75 said openings, means for receiving the blank when it falls through said openings, and means for moving said receiving 80 means.

37. In a machine for cutting blanks of 85 material in sheet form, feeding means for intermittently advancing said material, cutting means intermittently operating transversely of said sheet and comprising a cutting die having an opening therethrough, a support for said die having an opening therethrough corresponding to and in alignment with said first-mentioned opening, a cutting block, means for moving said block towards said die to perform the cutting operation and away from said die when the cutting operation is completed, and means associated with said block for freeing the blank 90 from the die and ejecting the same through 95 said openings.

38. In a machine for cutting blanks of 100 material in sheet form, feeding means for intermittently advancing said material, cutting means intermittently operating transversely of said sheet and comprising a cutting die having an opening therethrough, a support for said die having an opening therethrough corresponding to and in alignment with said first-mentioned opening, a cutting block, means for moving said block towards said die to perform the cutting operation and away from said die when the cutting operation is completed, and means associated with said block and operated by the cutting means for freeing the blank from the die and ejecting the same through 110 said openings.

In testimony whereof, I have signed my 115 name to this specification this eighth day of April 1919.

JOHN H. OVERTON.

Witness:

WALTER H. GRATTON.
